UNITED STATES PATENT OFFICE.

CHARLES M. DRINKWATER, OF KOKOMO, INDIANA.

ASH-SIFTING APPARATUS.

1,290,525.

Specification of Letters Patent.

Patented Jan. 7, 1919.

Application filed December 20, 1917, Serial No. 208,047. Renewed September 24, 1918. Serial No. 255,531.

To all whom it may concern:

Be it known that I, CHARLES M. DRINKWATER, a citizen of the United States, residing at Kokomo, in the county of Howard 5 and State of Indiana, have invented certain new and useful Improvements in Ash-Sifting Apparatus, of which the following is a specification.

My present invention pertains to chutes, 10 sifters, screens, and analogous apparatus, and more particularly to ash-sifting apparatus.

One of the objects of the invention is the provision of means for effectually keeping 15 down and preventing the dissemination of dust in the atmosphere; the said means being actuatable by the placing of a shovel on a wing thereof so that the weight of the shovel and substance thereon serves to open 20 a valve, and then when the contents of the shovel are discharged through the throat controlled by the valve, the valve is promptly closed so that no dust can escape from the throat. The throat, which is preferably 25 made to support the automatically closing valve and its appurtenances, may be made to form part of an ash sifting apparatus or part of any other apparatus to which it is applicable and upon which it may be used to 30 advantage, without involving departure from the scope of my invention as defined in my appended claims.

Another object of my invention is the provision of dust-confining means that is at 35 once, simple and compact in construction and reliable in operation, and is well adapted to withstand the rough usage to which apparatus of corresponding character is ordinarily subjected as well as expo- 40 sure to the weather.

Another object is the provision of an ash-sifting apparatus having an inclined screen, a door for the convenient removal of cinders from the compartment to which the screen 45 delivers, and a baffle-plate positioned in front of and spaced from the forward end of the screen so as to receive the impact of the descending cinders and thereby prevent the same from striking against and distort- 50 ing or otherwise injuring the door.

Another object is the provision of an ash-sifter body susceptible of being expeditiously and easily knocked down or taken apart so as to occupy but small compass in 55 storage or shipment, and one adapted to be

as readily set up with its parts joined in such manner that it is ready for efficient use, and this without the employment of skilled labor.

Another object of the invention is the 60 provision of an ash-sifting or kindred apparatus in which the throat supporting the automatic valve mechanism is joined to the body on which it is mounted in such manner that the escape of dust between the two 65 is absolutely precluded.

Other objects and advantageous features of the invention will be fully understood from the following description and claims when the same are read in connection with 70 the drawings, accompanying and forming part of this specification, in which:

Figure 1 is a longitudinal vertical section of an ash-sifting apparatus constituting the best practical embodiment of my invention 75 of which I am cognizant.

Fig. 2 is a vertical transverse section of the same, taken in the plane indicated by the line 2—2 of Fig. 1.

Fig. 3 is a top plan view of the apparatus. 80

Fig. 4 is a horizontal section, taken in the plane indicated by the line 4—4 of Fig. 1.

Fig. 5 is a detail view in vertical section, showing the dust-confining means with the working parts in the positions they are 85 caused to assume when the weight of a shovel, hod or the like and its contents is imposed on the swinging wing.

Fig. 6 is a detail vertical transverse section, taken in the plane indicated by the 90 line 6—6 of Fig. 5.

Similar numerals of reference designate corresponding parts in all of the several views of the drawings.

In the preferred embodiment of my in- 95 vention all of the parts of the apparatus, with the exception of the elements explicitly referred to as formed of other material, are made of galvanized sheet iron.

For the sake of convenience I will first 100 describe the construction and mode of operation of the valve for confining and preventing the dissemination of dust, and the throat for supporting the said valve and the appurtenances of the valve—i. e., the 105 elements that coöperate with the valve for the purpose stated.

In the present embodiment the throat 110 is of about the proportional height illustrated; and is rectangular in configuration.

Fixed to the forward transverse wall and the side walls of the said throat, at the upper edges of said walls, and extending inwardly and outwardly from the walls are 5 inclined walls 2 which form a flaring mouth, Figs. 1, 2, 5 and 6, calculated to effectually prevent the spilling of ashes about the apparatus when the shovel, hod or other receptacle employed for the conveyance of the 10 ashes is dumped into the throat. At their rear or inner ends the side walls 2 are flanged, as indicated by 3, Fig. 6, to form stops, designed and adapted to limit the opening movement of the valve 4. The said 15 valve 4 is arranged to close upwardly flat against the lower and inner edges of the mouth walls 2 and downwardly flat against the upper edge of the rear or inner transverse wall of the throat 1 so as to make a 20 dust-tight closure; and it is fixed at a point adjacent to its rear edge on a transverse shaft 5, journaled in the side walls of the throat 1, and disposed in a transverse vertical plane immediately below the stop 25 flanges 3. At one end the said shaft 5 is provided with a spur gear 6, suitably fixed thereto.

Journalized in brackets 7, fixed to the sides of the throat 1 and extending upwardly and 30 rearwardly beyond the rear upper corner thereof, is a transverse shaft 8, arranged in parallel relation to the shaft 5. The shaft 8 is equipped with a spur gear 9, and said gear 9 is intermeshed with the gear 6. The 35 said shaft 8 also serves for the connection of the wing 10; the said wing being fixed adjacent to its forward and lower edge to the shaft in the manner illustrated or in any other manner compatible with the purposes 40 of my invention. Attention is also directed here to the fact that the valve 4 and the wing 10 are so relatively arranged that when the valve is in closed position, the lower and forward edge of the slightly inclined wing will be opposed to the upper side of the valve at a point immediately 45 above the center of movement of the latter. Because of this relative arrangement the lower and forward edge of the wing 10 will 50 always lap the rear edge of the valve 4 and consequently there will be little or no liability of cinders lodging between the adjacent edges of the valve and wing and interfering with the free working of the mechanism.

At a point outwardly beyond the spur gear 9 the shaft 8 carries a counterbalance weight 11, the function of which is to promptly close the valve 4 after said valve 60 is canted downwardly and is discharged of a deposit of commingled cinders and ashes.

The operation of the portion of my improvement described in detail in the foregoing is as follows:—

65 The shovel, hod or other receptacle in

which ashes are carried is placed upon the wing 10 whereupon the weight of the shovel or hod and the contents thereof will depress the said wing to the extent indicated clearly by full lines in Fig. 5. The said depression 70 or downward movement of the wing 10 will, by reason of the gear connection described, be attended by downward movement of the valve 4 which valve will assume the downwardly and forwardly inclined position 75 shown in Fig. 5. Then when the shovel, hod or the like is discharged of its contents, the wing 10 forming a convenient support for the shovel or hod during said manipulation, the said contents will be received on the 80 valve 4 and will be chuted by the same into the interior of the throat 1, whereupon, the shovel, hod or other receptacle having been removed, the weight 11 will immediately return the valve 4 and the wing 10 to their 85 normal positions, with the result that the escape of dust from the throat will be absolutely precluded.

It will be appreciated from the foregoing that the connected and coöperating valve 90 and wing constitute important features of my invention; also that said valve and wing and their appurtenances are simple and compact in construction, efficient and reliable in operation, and well adapted to withstand 95 rough usage and shock and jar when a loaded shovel, hod or other receptacle is suddenly brought to bear on the wing.

As hereinbefore indicated my invention is preferably, though not necessarily embodied in an ash-sifting apparatus, and in addition to the throat 1 and its appurtenances that have been described in detail, the said apparatus comprises a body 12 on which the throat 1 is superimposed, Fig. 1, 100 an inclined screen 13 in the body, a vertically-slidable door 14 disposed in guides at the forward end of the body for the convenient removal of cinders from the forward portion of the body bottom, a baffle plate 15 105 disposed at approximate right angles to the screen 13 and in spaced relation to the lower end thereof, a compartment 16 below the screen and isolated from the cinder compartment 17 by a transverse wall 18, and a drawer 19 designed to receive ashes and having handles 20 and 21 at its opposite ends; the handle 21 for convenience in lifting and moving being disposed within the drawer, and the drawer being removable 110 through an opening in the forward wall of body 12 and being flanged, as indicated by 22, to effectually close said opening when the drawer is in position to receive ashes, as 115 shown in Fig. 1.

As clearly shown in Fig. 1 and Fig. 2, the lower end of the throat 1 is provided with loop-flanges 23 that straddle the upstanding wall portions about the induction orifice of the body 12. Thus the throat is 120 125 130

supported on the body in such manner that the joint between the two is broken and the escape of dust precluded, and yet the throat may when necessity arises be readily lifted 5 off the body and as readily replaced thereon.

The side walls 24 of the body 12 are provided on their upper edges with inwardly-directed flanges 25, Figs. 3 and 4, and the top wall 26 is interlocked with said flanges 10 25, as indicated by 27 to break joints between the parts, strongly connect the same, and lend rigidity and strength to the body as a whole, as well as to permit of the wall 26 being drawn out of engagement with the 15 walls 24 when it is desired to ship or store the body in a knock-down state. At its lower end the wall 26 is interlocked with the upper end of the baffle plate 15, as indicated by 28, Fig. 1, and at its upper end 20 said wall 26 is interlocked with an upstanding wall portion, as indicated by 29. Thus when it is desired to remove the wall 26 from walls 24, it is simply necessary as a condition precedent to open the joints 28 25 and 29 whereupon the wall 26 may be withdrawn endwise from the position shown in Fig. 1.

The bottom wall 30 of the body 12 is connected by interlocked joints 31, Fig. 2, 30 with the side walls 24, and hence said bottom wall is strongly connected to the side walls in a dust-proof broken joint manner, and yet the bottom wall may be readily withdrawn from engagement with the side walls 35 for knock-down purposes.

Fig. 4 brings out clearly the connection of the front wall 32 of the body 12 to the side walls 24 thereof through the medium of interlocked joints 33 for dust-proof and 40 strength-lending purposes as well as to permit of the front wall being readily drawn out of engagement with the side walls for knock-down purposes, while the screen 13 is bolted to the side walls 24, as indicated 45 by 34, the baffle plate 15 and wall 18 are also bolted to said side walls, as indicated by 35 and 36, respectively, the wall 18 is bolted to the screen 13, as indicated by 37, and the said screen is bolted to the front wall 50 32, as indicated by 38. Manifestly when the said bolts are removed, the body walls may be disassembled in the manner before indicated for the purposes described, and when the said walls are relatively arranged 55 and engaged in the setting up of the body and the bolts are placed and secured in position a rigid and strong body will be produced.

The parts of my novel apparatus that 60 are formed of metal other than galvanized sheet iron, are the shafts, the gears thereon, the counterbalance weight, the brackets, and the connecting bolts.

When deemed expedient the screen 13 65 may be mounted in the body 12 so as to be

slipped endwise into and out of working position, as when it is desired to use screens having interstices of different sizes or to replace a worn-out screen with a new one. This, however, is not of the essence of my 70 invention and I have therefore regarded it as unnecessary to illustrate same.

I have entered into a detail description of the construction and relative arrangement of the parts embraced in the present and preferred embodiment of my invention in order to impart a full, clear and exact understanding of the said embodiment. It is to be understood, however, that in the future practice 75 of the invention such changes or modifications in the construction may be made as are fairly anticipated by and fall within the scope of my appended claims.

Having described my invention, what I 80 claim and desire to secure by Letters Patent, is:

1. The combination of a throat, a dust-confining valve therein, a wing upon which a shovel, hod or other receptacle may be rested incidental to the discharge of the 90 contents thereof into the throat, a connection intermediate the valve and the wing for opening the former on downward movement of the latter, and means for closing the valve and raising the wing when weight 95 is removed from the latter.

2. The combination of a throat, a dust-confining valve therein, a wing upon which a shovel, hod or other receptacle may be rested incidental to the discharge of the 100 contents thereof into the throat, a connection intermediate the valve and the wing for opening the former on downward movement of the latter, and a counterbalance weight constructed and arranged to close 105 the valve and raise the wing when the latter is relieved of weight.

3. The combination of a throat having a flared mouth, a dust confining valve therein below and arranged to close upwardly 110 against said mouth and downwardly against a wall of the throat, a wing upon which a shovel, hod or other receptacle may be rested incidental to the discharge of the contents thereof into the throat, a connection intermediate the valve and the wing for opening the former on downward movement of the latter, and means for closing the valve and raising the wing when the latter is relieved 115 of weight.

4. The combination of a throat having a flared mouth, a dust confining valve therein below and arranged to close upwardly against said mouth and downwardly against a wall of the throat, a wing upon which a shovel, hod or other receptacle may be rested 125 incidental to the discharge of the contents thereof into the throat, a connection intermediate the valve and the wing for opening the former on downward movement of 130

the latter, and a counterbalance weight constructed and arranged to close the valve and raise the wing when the latter is relieved of weight.

5. The combination of a throat, movable dust-confining means therein, movable means upon which a shovel, hod or other receptacle may be rested incidental to the discharge of the contents thereof into the throat, and 10 means intermediate the second-named means and the first-named means for moving the latter by the former.

6. The combination of a throat, movable dust-confining means therein, movable means 15 upon which a shovel, hod or other receptacle may be rested incidental to the discharge of the contents thereof into the throat, means intermediate the second-named means and the first-named means for moving the latter 20 by the former, and means for returning the first-named means and the second-named means to their normal positions.

7. The combination of a throat, a pivoted dust-confining valve therein, a pivoted wing 25 upon which a shovel, hod or other receptacle may be rested incidental to the discharge of the contents thereof into the throat, intermeshed gears connecting the pivoted valve and wing, and means for closing the valve 30 and raising the wing when weight is removed from the latter.

8. The combination of a throat, a pivoted dust-confining valve therein, a pivoted wing upon which a shovel, hod or other receptacle 35 may be rested incidental to the discharge of the contents thereof into the throat, intermeshed gears connecting the pivoted valve and wing, and a counterbalance weight constructed and arranged to close the valve and 40 raise the wing when the latter is relieved of weight.

9. The combination of a throat, transverse shafts supported thereby, a dust-confining valve fixed to one shaft and disposed in 45 the throat, a wing fixed to the other shaft and upon which a shovel, hod or other receptacle may be rested incidental to the discharge of the contents thereof into the throat, intermeshed gears fixed on said 50 shafts, and means for closing the valve and raising the wing when weight is removed from the latter.

10. The combination of a throat, transverse shafts supported thereby, a dust-confining valve fixed to one shaft and disposed 55 in the throat, a wing fixed to the other shaft and upon which a shovel, hod or other receptacle may be rested incidental to the discharge of the contents thereof into the 60 throat, intermeshed gears fixed on said shafts, and a counterbalance weight on one shaft.

11. The combination of a throat having a flared mouth, transverse shafts supported by 65 said throat, a dust-confining valve fixed to

one shaft and arranged to close upwardly against said mouth and downwardly against a wall of the throat, a wing fixed to the other shaft and upon which a shovel, hod or other receptacle may be rested incidental to the 70 discharge of the contents thereof into the throat, and intermeshed gears connecting the shafts.

12. The combination of a throat having a flared mouth, transverse shafts supported by 75 said throat, a dust-confining valve fixed to one shaft and arranged to close upwardly against said mouth and downwardly against a wall of the throat, a wing fixed to the other shaft and upon which a shovel, hod or other 80 receptacle may be rested incidental to the discharge of the contents thereof into the throat, and a counterbalance weight on one shaft.

13. The combination of a throat having 85 an inclined transverse wall and inclined side walls forming a flared mouth and also having stop flanges at the rear or inner ends of the side walls, transverse shafts supported by said throat and arranged adjacent to said 90 stop flanges, a dust-confining valve fixed to one shaft and arranged to close upwardly against the lower edges of the mouth walls and downwardly against the upper edge of the rear or inner wall of the throat, a wing 95 fixed to the other shaft and upon which a shovel, hod or other receptacle may be rested incidental to the discharge of the contents 100 thereof into the throat, and means for transmitting turning movement from one shaft to the other.

14. The combination of a throat having an inclined transverse wall and inclined side walls forming a flared mouth and also having stop flanges at the rear or inner ends of the side walls, transverse shafts supported by said throat and arranged adjacent to said 105 stop flanges, a dust-confining valve fixed to one shaft and arranged to close upwardly against the lower edges of the mouth walls and downwardly against the upper edge of the rear or inner wall of the throat, a wing fixed to the other shaft and upon which a shovel, hod or other receptacle may be rested 110 incidental to the discharge of the contents thereof into the throat, means for transmitting turning movement from one shaft to the other, and means for raising the valve.

15. The combination of a throat having an inclined transverse wall and inclined side 120 walls forming a flared mouth and also having stop flanges at the rear or inner ends of the side walls, transverse shafts supported by said throat and arranged adjacent to said stop flanges, a dust-confining valve fixed to one shaft and arranged to close upwardly 125 against the lower edges of the mouth walls and downwardly against the upper edge of the rear or inner wall of the throat, a wing fixed to the other shaft and upon which a 130

shovel, hod or other receptacle may be rested incidental to the discharge of the contents thereof into the throat, intermeshed gears connecting the shafts, and means for 5 raising the valve.

16. The combination of a throat having an inclined transverse wall and inclined side walls forming a flared mouth and also having stop flanges at the rear or inner ends 10 of the side walls, transverse shafts supported by said throat and arranged adjacent to said stop flanges, a dust-confining valve fixed to one shaft and arranged to close upwardly against the lower edges of the mouth walls 15 and downwardly against the upper edge of the rear or inner wall of the throat, a wing fixed to the other shaft and upon which a shovel, hod or other receptacle may be rested incidental to the discharge of the contents 20 thereof into the throat, means for transmitting turning movement from one shaft to the other, and a counterbalance weight on one shaft.

17. The combination of a throat having 25 an inclined transverse wall and inclined side walls forming a flared mouth and also having stop flanges at the rear or inner ends of the side walls, transverse shafts supported by said throat and arranged adjacent to 30 said stop flanges, a dust-confining valve fixed to one shaft and arranged to close upwardly against the lower edges of the mouth walls and downwardly against the upper edge of the rear or inner wall of the throat, a wing 35 fixed to the other shaft and upon which a shovel, hod or other receptacle may be rested incidental to the discharge of the contents thereof into the throat, intermeshed gears connecting the shafts, and a counterbalance 40 weight on one shaft.

18. The combination of a throat having an inclined transverse wall and inclined side walls; said walls extending within and without the upper edges of the throat walls, a 45 pivoted valve disposed in the throat and arranged to close upwardly against the mouth walls and downwardly against the rear or inner wall of the throat, a pivoted wing the lower edge of which is opposed to the upper 50 side of the wall, means connecting the valve and wing, and means for raising the valve to a normally-closed position.

19. The combination of a throat having an inclined transverse wall and inclined side 55 walls; said walls extending within and without the upper edges of the throat walls, a pivoted valve disposed in the throat and arranged to close upwardly against the mouth walls and downwardly against the rear or inner wall of the throat, a pivoted wing the lower edge of which is opposed to the upper 60 side of the wall, intermeshed gears connecting the valve and wing, and means for raising the valve to a normally-closed 65 position.

20. The combination of a throat having an inclined transverse wall and inclined side walls; said walls extending within and without the upper edges of the throat walls, a pivoted valve disposed in the throat and arranged to close upwardly against the mouth walls and downwardly against the rear or inner wall of the throat, a pivoted wing the lower edge of which is opposed to the upper 70 side of the wall, intermeshed gears connecting the valve and wing, and a counterbalance weight constructed and arranged to raise the valve to a normally-closed position. 75

21. The combination of a throat having an inclined transverse wall and inclined side 80 walls; said walls extending within and without the upper edges of the throat walls, a pivoted valve disposed in the throat and arranged to close upwardly against the mouth walls and downwardly against the rear or inner wall of the throat, a pivoted wing the lower edge of which is opposed to the upper 85 side of the wall, shafts supported by the throat and carrying the valve and the wing, respectively, intermeshed gears 90 fixed on said shafts, and a counterbalance weight fixed on one shaft.

22. The combination of a throat, a swinging valve arranged therein and constructed and arranged to receive a load and chute 95 the same into the throat, movable means constructed and arranged relative to the throat to serve as a rest for a receptacle incidental to the dumping of the load of the latter into the throat and also constructed and arranged 100 to be depressed by the weight of receptacle and contents, and means for swinging the valve downwardly into open position upon depression of said movable means. 100

23. The combination of a throat, a swinging valve arranged therein and constructed and arranged to receive a load and chute the same into the throat, movable means constructed and arranged relative to the throat to serve as a rest for a receptacle incidental 110 to the dumping of the load of the latter into the throat and also constructed and arranged to be depressed by the weight of receptacle and contents, means for swinging the valve downwardly into open position upon depression of said movable means, and means for closing the valve when the movable means is relieved of weight. 115

24. The combination of a throat, movable dust-confining means therein, movable means 120 constructed and arranged relative to the throat to serve as a rest for a receptacle incidental to the dumping of the load of the latter into the throat and also constructed and arranged to be depressed by the weight 125 of receptacle and contents, and means for opening the dust-confining means upon depression of said movable means.

25. The combination of a throat, movable dust-confining means therein, movable means 130

constructed and arranged relative to the throat to serve as a rest for a receptacle incidental to the dumping of the load of the latter into the throat and also constructed and arranged to be depressed by the weight of receptacle and contents, means for opening the dust-confining means upon depression of said movable means, and means for closing the dust-confining means when said movable means is relieved of weight.

26. The combination of a throat, movable means constructed and arranged relative to the throat to serve as a rest for a receptacle incidental to the dumping of the contents thereof into the throat and also constructed and arranged to be depressed by the weight of receptacle and contents, and normally-closed dust-confining means in the throat actuatable to open position by depression of said movable means.

27. The combination of movable dust-confining means, a movable receptacle rest, and means for opening the dust-confining means

when a receptacle is superimposed on the receptacle rest.

28. The combination of movable dust-confining means, a movable receptacle rest, means for opening the dust-confining means when a receptacle is superimposed on the receptacle rest, and means for closing the dust-confining means upon removal of weight from the receptacle rest.

29. The combination of an automatically closing valve, and means connected with said valve and constructed and arranged to bring about the opening of the valve when a loaded receptacle is superimposed on said means incidental to the discharge of its contents past the valve.

In testimony whereof I affix my signature in presence of two witnesses.

CHARLES M. DRINKWATER.
